UNITED STATES PATENT OFFICE.

WALTER M. PRATT, OF DETROIT, MICHIGAN.

INSERT FOR CONCRETE CONSTRUCTION.

1,281,416.

Specification of Letters Patent. Patented Oct. 15, 1918.

Application filed February 10, 1917. Serial No. 147,835.

To all whom it may concern:

Be it known that I, WALTER M. PRATT, a citizen of the United States, residing at Detroit, in the county of Wayne and State of Michigan, have invented a new and useful Insert for Concrete Construction, of which the following is a specification.

The invention relates to inserts for concrete construction, and its object is to provide an insert comprising an elongated channel member adapted to be embedded and anchored in a reinforced concrete floor or other concrete structure, and a rider retained in the channel of said member and slidably adjustable therein, said rider being formed with a screw-threaded opening or otherwise adapted to be detachably engaged by a bolt or other hanger.

In the drawings, Figure 1 is a side elevation of the insert as applied to a reinforced concrete floor; Fig. 2 is a bottom view of the same; Fig. 3 is a section on 3—3 of Fig. 1; Figs. 4, 5, and 6 are corresponding views of a modified form.

In these views, the reference character 1 designates a concrete floor, having two transversely arranged sets of reinforcing bars 2 and 3 extending horizontally in its lower portion. Embedded in said floor is a channel member 4, formed preferably of sheet-metal, the sides of said member being inclined downwardly toward each other, so as to form a slot 5 between their lower extremities, and said extremities being formed with out-turned flanges 6 flush with the under surface of the floor. At intervals the inclined walls of the member 4 are formed with pairs of opposite slots 7, adjacent the top of said member. In each pair of these slots there are engaged the inturned lower ends 8 of an arch-shaped anchorage member 9, which may be formed of bar iron. The members 9 are embedded in the central portion of the floor and are sufficiently numerous to resist the maximum downward pull to which the channel member may be subjected.

A slidably adjustable rider is engaged with the member 4, which rider comprises a flared head 10 within the channel and resting upon the inclined sides thereof, a body 11, preferably of cylindrical form, projecting some distance below the floor, and shoulders 12, projecting laterally beneath the respective flanges 6 and having top surfaces parallel and adjacent to said flanges. A central threaded opening 13 extends up into the

body of the rider from the bottom thereof, and an inverted bolt 14 has its shank engaged in said opening. The headed lower end of the bolt may be engaged with a shaft 6c hanger, pipe hanger, (not shown) or any other member which is to be supported from the ceiling.

At any desired point in the channel member, the slot 5 is widened to form an entrance slot 15 by stamping opposite tongues from the lower portion of the inclined side walls of said member and from the flanges 6. The upper portions 16 of these tongues are bent into vertical parallelism and their lower portions 17 are in the plane of the flanges and project somewhat beyond the same. The dimensions of said entrance slot are a trifle greater than those of the head 10 at the widest part of the latter, so that when the channel is in place in the floor, the rider or riders may be engaged with or disengaged from the channel by use of said entrance slot. Holes 18 may be provided in the flanges 6 at suitable intervals, 80 and nails or other fastening means (not shown) may be driven through these holes and into the forms to hold the channel members and anchorage members securely in place during pouring. In order to prevent the concrete from flowing into the channels as it is being poured, sheet-metal caps 19 are frictionally engaged with the extremities of the channel member 4.

In that form of the invention shown in Figs. 4, 5, and 6, there is used a channel member and anchorage members substantially as above-described, and for these parts the reference characters are the same as in the first three figures. In this modification however the rider takes the form of a metal block 20 insertable as a whole into engagement with the channel, the lower portions of the sides being beveled as in the first-described rider to rest upon the inclined walls of the channel, but the upper portions of said sides being recessed as indicated at 21 as a clearance for the inturned ends of the anchorage members 9, while the top portion of the block projects between said ends. A screw-threaded opening 22 extends centrally and vertically entirely through this rider, and is engaged by the shank of a bolt 23.

Numerous advantages which will now be explained are derived from the above-described construction. Concrete floors are commonly reinforced by one or more series

of rods, extending horizontally and embedded at the minimum distance above the floor bottom to afford adequate fire-proofing. Thus in the drawings, two transversely arranged series 24 and 25 are shown, forming the well-known "two way" system. For practically all reinforced concrete work, the minimum thickness of material below the reinforcement is three-fourths of an inch. To exceed this is highly undesirable since any thickness below the reinforcements in excess of the fire-proofing requirements is entirely wasted, and uselessly increases the weight of the floor. Slotted channel inserts have hitherto been employed, shaped to slidably engage the heads of standard bolts, but in order to accommodate the bolt-heads, it has been requisite to give the channel members a height greater than the thickness of material required for fire-proofing, and consequently space the bars extending transversely above said channel members an undesirable distance above the floor bottom. In the present invention, the usual fire-proofing area below the bars is ample to embed the channel members, since the portions of the riders engaged within the channels are given horizontal dimensions such as to secure adequate strength, with little height. Furthermore, said riders do not concentrate the downward pull which they transmit, as vertical stresses in the concrete but because of the abutting inclined faces produce a horizontal component of said pull. The anchorage required is thus reduced as compared with an insert in which the downward pull has no horizontal component. The corresponding inclined faces of the channel walls and the rider further has the effect of causing the rider to become wedged more firmly in place by each increase in the load which it transmits to the floor. In the form of the invention shown in the first three figures the shoulders 12 through their proximity to the flanges 6 serve to prevent lateral rocking of the rider when under load. This form of rider is especially suitable where it is permissible to engage the bolt with the rider below the floor, while the form shown in Figs. 4, 5, and 6 may be used where it is desired to have the rider con-

tained completely within the channel. It is to be noted that the anchorage members are engaged with the channel members so as to be restrained against longitudinal motion, thus eliminating necessity for adjustment of said anchorage members as the inserts are being arranged on the forms. 55

What I claim is:

1. The combination with an insert comprising a channel member having its walls inwardly inclined and a rider having a portion within the channel of said member supported upon said walls and having integral lateral projections exterior to and below the channel member, of means associated with the channel member at each side thereof co-acting with said projections to restrain the rider from wabbling. 60
2. An insert, comprising a channel member having its walls inwardly inclined and having out-turned flanges at the bottoms of said walls, and a rider having a portion within the channel of said member supported upon said inclined walls and having integral portions extending adjacent to said flanges beneath the same. 70
3. The combination with an insert comprising a channel member and a rider adjustably retained in the channel of said member and having integral lateral projections below said member, of means associated with the channel member at each side thereof for restraining the rider from wabbling. 75
4. An insert, comprising a channel member having flanges projecting laterally from its side walls and a rider having a portion adjustably retained in the channel of said member and having integral portions projecting laterally in proximity to said flanges. 80
5. An insert, comprising a sheet-metal channel member having its walls inwardly inclined and having said walls respectively flanged laterally at their bottoms to reinforce said wall a rider having a portion within the channel of said member, supported upon said inclined walls, said rider having a threaded orifice, and a hanger engaged with said orifice. 90
